By A. Miller Belfield Atty

UNITED STATES PATENT OFFICE.

SEVERIN HALVORSEN, OF CHICAGO, ILLINOIS, ASSIGNOR TO THE NEWSPAPER STUFFING MACHINE COMPANY, OF SEATTLE, WASHINGTON, A CORPORATION OF WASHINGTON.

AUTOMATIC STOPPING MEANS.

Original application filed May 20, 1922, Serial No. 562,462. Divided and this application filed June 5, 1924. Serial No. 718,169.

My invention relates to means for automatically stopping machinery, particularly in case of trouble or defective action in the operation of the machinery.

5 The principal object of the invention is to provide simple, practical and advantageous automatic stopping means.

Another object of the invention is to provide a construction by which certain and reliable results may be secured.

10 This application is a division of my application Serial No. 661,816, filed September 10, 1923, for signaling, indicating, stopping and starting devices, which application in turn

15 is a division of my application Serial No. 562,462, filed May 20, 1922.

20 In the accompanying drawings I show the invention applied to a machine for stuffing newspapers, but it will be readily seen and understood that the invention is capable of various other applications and uses.

25 In the drawings Fig. 1 is an end view partly in cross section of the newspaper stuffing machine provided with an automatic stopping mechanism embodying my present invention;

Fig. 2 is a side elevation of the automatic stopping mechanism;

30 Fig. 3 is a longitudinal section of a portion of such mechanism; and

Fig. 4 is a cross section taken on line 4—4 in Fig. 2.

35 Referring to the drawings, I show a newspaper stuffing machine which is not claimed of itself herein, and which accordingly will not be described at length. In general it may be said to be provided with a trough 1 into which newspaper and cover sections 2 are fed, and then moved along the trough 1.

40 As moved along, insert sections 3, 4 and 5 are fed into the cover sections 1 and then the completed or stuffed paper is discharged.

45 In Fig. 1 I show chains 6—6 for moving the paper sections along the trough 1, and these are driven by other chains 7—7 by means of a drive shaft 8 connected by pinions 9 and 10 with a vertically arranged shaft 11 which is in turn connected by pinions 12 and 13 with another and for present purposes a main drive shaft 14.

50 In newspaper stuffing machines such as above set forth, it is possible that at times there may be defective feeding of the paper

sections or clogging in some way of the sections in the trough 1, and this may result in 55 forcing such a jam in the trough that a heavy strain will be brought on the machinery and some breakage might result in case that strain was not relieved. Such a dangerous strain might result in the machine from 60 other causes.

In accordance with my invention I provide means by which the machine will be automatically stopped in case a dangerous strain develops in the machine, either from clogging 65 of paper sections in the trough, or otherwise.

To such end I make the drive shaft 14 jointed, having two parts 14^a and 14^b (Fig. 2), and connect these two parts together so that 70 normally they will automatically drive as a single shaft, but in case a dangerous strain takes place, one part will be stopped by the strain before the same reaches the danger point and the entire machine thereupon be 75 stopped, thereby avoiding injury or damage to the machine and allowing opportunity for removal of the trouble.

In the arrangement herein shown, which is one of a number of desirable arrangements which could be employed, I connect the shaft sections 14^a and 14^b together by means of a pin 15 which is of sufficient strength to cause the part 14^b which is connected with the motor or prime mover or main driving shaft, 85 to turn the part 14^a during all normal conditions, but said pin 15 is sufficiently weak to result in its being broken in case an undue strain occurs to mechanism attached to the shaft section 14, as for example a jam in the 90 trough 1 resulting in the bringing of a heavy strain upon the mechanism moving the paper sections in the trough, and thereby imposing such heavy strain upon the shafts 8 and 11.

I further provide an electrical connection 95 arrangement by which an electrical circuit may be closed when pin 15 is broken and shaft section 14^a is stopped and section 14^b is therefore allowed to move by itself, which electrical connection automatically stops the 100 prime mover or disconnects or stops the main driving shaft, thereby stopping the entire machine.

The electrical connection shown comprises a pin 17 mounted in a slot 18 in a collar 105 or head 19 on shaft section 14^b, said pin 17

being subject to a spring 20 tending to force it out of said slot 18. Pinion 13 is provided with an insulating strip or segment 22, against which pin 17 normally is pressed, 5 said pin 17 contacting with the metal of pinion 13, however, when pin 15 is broken and shaft section 14^b with collar 19 moves or rotates relatively to shaft section 14^a and pinion 13. A metal collar 23 with radial 10 flange 24 is provided and fitted on an insulating sleeve 25 having an annular projecting portion 26, on which metal collar 23 fits, and an insulating disk 27 is fitted on the other side of metal flange 20, thereby 15 insulating said collar 23 and flange 24. The members 19 and 25 are fast on shaft section 14^b, so that said section 14^b will turn section 14^a through pin 15. Member 19 has an insulating sleeve 28 in which pin 17 fits and 20 moves. Spring 20 makes contact with flange 24 through aperture in disk 27, thereby establishing electrical communication between pin 17 and collar 23 but said pin is otherwise insulated by reason of insulation 26, 27 25 and 28. A brush 30 fits on collar 23 which thereby acts as a commutator and an electrical conductor 31 is connected by binding post 32 with brush 30 and supported by bracket 33 so that electrical connection may 30 be made between conductor 31 and pin 17, as a result of which when pin 14 breaks pin 17 will complete an electrical circuit from 31 to pinion 13 and shaft section 14^a, and this 35 electrical circuit may contain any suitable stopping mechanism, as for example, a switch which may be arranged so that when its circuit is closed it will open a motor circuit, the motor forming the prime mover for the machine, or the circuit when closed may 40 operate a magnetic device capable of shifting

a belt or otherwise throwing power off from the machine in case it is direct driven by some power mechanism or shafting.

Thus it will be seen that the invention 45 permits the automatic stopping of the machine in case a dangerous strain is placed upon it, and that this is accomplished in a simple and expeditious manner.

It will be understood that changes and modification may be made without departing 50 from the spirit of the invention.

What I claim is:

1. In a machine of the character described, the combination of shaft sections, means providing a connection between said sections, 55 one of said sections having an insulating block, the other having a movable contact making element which is held out of electrical connection by means of said block, said movable contact making element being 60 movable relatively to said block to thereby complete an electrical connection upon the separation of the connection.

2. The combination of separate shaft sections, one of which is provided with a metallic member having an insulating block and the other of which is provided with an insulating sleeve carrying a commutator ring and a metallic member mounted on said insulating sleeve and containing an insulating sleeve having a pin adapted normally to contact with said insulating block, a spring tending to push said pin outwardly, a pin 70 between the metallic members on said shaft sections and a brush on the metallic member on the second mentioned shaft section. 75

In witness whereof, I hereunto subscribe my name this 28th day of May, A. D., 1924.

SEVERIN HALVORSEN.
